(57) **CLAIM**

The ornamental design for a facial cleaning brush, as shown and described.

DESCRIPTION

FIG. 1 is a perspective view of a facial cleaning brush pumping bra showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the facial cleaning brush on a cradle.

The broken line showing of the cradle feature in FIG. 9 depicts environment and forms no part of the claimed design. All other broken lines depict portions of the facial cleaning brush that form no part of the claimed design.
